United States Patent Office

Des. 202,156
Patented Aug. 31, 1965

202,156

CEILING HEATER

Harold L. Herman, 7319 Lankershim Blvd.,
Burbank, Calif.

Filed June 22, 1964, Ser. No. 80,513

Term of patent 14 years

(Cl. D81—10)

FIG. 1.

FIG. 2.

FIG. 3.

FIG. 1 is a perspective view taken from the bottom and two sides of the ceiling heater embodying my new design.

FIG. 2 is a side view taken in the direction of the arrow 2 in FIG. 1.

FIG. 3 is a bottom view.

The side not shown is the same as the side shown at the left in FIG. 1.

I claim:

The ornamental design for a ceiling heater, as shown and described.
